TOY GUN

Charles F. Lefever, Plymouth, Mich., assignor to
 Daisy Manufacturing Company, Plymouth,
 Mich., a corporation of Michigan

Application March 11, 1935, Serial No. 10,553

5 Claims. (Cl. 46—10)

The invention relates to toy guns of that type in which the gun when fired will make a loud report without discharging a projectile. It is one of the objects of the invention to obtain a 5 construction in which the pulling of the trigger causes a flash in addition to the sound. It is a further object to obtain a repeater, that is, a construction in which the gun will successively produce the flash and report each time the trigger 10 is pulled, without requiring any other action. A further object is to obtain a construction which in appearance simulates the known type of repeating fire arms, and still further it is an object to simplify construction and reduce the cost of 15 manufacture. With these objects in view, the invention consists in the construction as herein-after set forth.

In the drawing:

Fig. 1 is a vertical central longitudinal section 20 of the gun;

Fig. 2 is a perspective view of the operating unit disengaged from the barrel and frame of the gun;

Figs. 3 and 4 are elevations of the translucent 25 cover and supporting frame for the sparking chamber;

Fig. 5 is a perspective view of the air cylinder detached;

Fig. 6 is a cross section on line 6—6, Fig. 2.

The barrel A, frame B and handle C of the gun are formed integral with each other and of 30 two complementary stampings meeting in the central plane. The frame is provided with a raised portion B' having on opposite sides thereof windows which are covered by a translucent 35 material. This material D is held in place by an annular frame D' held on the inside of the frame B' by ears D² extending through slots in said frame B'.

The translucent material is notched at D³ to engage the ears D² and to thus be held from misplacement. Within the barrel portion is an air cylinder E which is preferably secured 40 in position by striking out a loop E' from one side near its rear end and engaging this loop by a tongue E² on one section of the barrel intermediate two notches E³ cut in said barrel. In front of the air cylinder is the pop mechanism comprising a metal disk F adapted to seat upon a flange E⁴ at the forward end of the barrel, said

flange being of a diameter reduced from that of the barrel. The disk is pressed towards its seat by the tension of a helical spring F' which is inserted through the muzzle end of the barrel and has its forward coil engaged with tongues F²

struck inward from the barrel and projecting rearward.

The operating mechanism is formed as a unit which can be placed between the complementary sections of the barrel and frame and is of the following construction: G is a plate having its rear portion adapted to fit within the frame and to be secured thereto by ears G' extending through slots in said frame. This plate has a forwardly extending portion G³ which is bent into a U form 10 to constitute a guide for the plunger shank. There is also an inverted U portion G⁴ at the rear end of the frame forming another guide for the plunger shank. Centrally of the frame portion is an upwardly extending portion G⁵ having 15 window openings therein and there is a flange G⁶ at the upper end of this portion, said flange having its forward end bent downward at G⁷. The plunger H is of the usual type comprising a felt washer H' between metal washers H² which 20 are secured on the plunger shank H³. This shank has a forwardly projecting portion H⁴ adapted when the plunger is at the forward end of the barrel to unseat the disk F from the flange E⁴. The plunger shank extends rearward through the 25 U-shaped guide G³ and is then upwardly offset to form a portion H⁵ which extends rearward and engages the inverted U guide G⁴. The end of the shank is bent down at H⁶ to engage the sear. The trigger I is pivoted to the plate G just 30 below the offset portion H⁵ of the shank, being secured between said plate and a struck-out U-shaped flange G⁸. The pivot pin I' passes through said flange, trigger and plate. The trigger is preferably formed of sheet metal, being 35 of U-shaped cross section and having the rearwardly extending bifurcated arm I². I³ is a link between the furcations of the arm I² and pivotally secured thereto at its lower end. The upper end of this link is curved rearward and downward and is provided with a shoulder I⁴ forming the sear for engaging the portion H⁶ of the shank. The lower end of the link I³ has a hooked arm I⁵ which is connected to a spring J anchored to an ear G⁸ on the plate G. In rear of the inverted U-guide G⁴ an obliquely extending flange G⁹ is struck out of the plate G to extend in the path of the link I³ when the latter is moved rearward by the pulling of the trigger. The construction is such that when the trigger is pulled it will 40 move the link I³ rearward carrying with it the plunger shank H³ through the engagement of the downturned hook H⁶ with the sear I⁴. When the link is moved a sufficient distance to contact its rear end with the flange G⁹, this flange will 45

force it downward, disengaging the sear I^4 from the hook H^6 and permitting the plunger and shank to move forward. This forward movement is effected by a helical spring K surrounding the 5 shank and the U-shaped guide G^3 being provided with an abutment G^{10} at the rear end of said guide. The return or forward movement of the trigger is caused by the spring J and this movement is limited by a struck-up flange G^{11} with 10 which the trigger contacts.

The means for forming the flash comprises a tubular holder L mounted on the flange G^6 and containing a stick of sparking metal L' . This is pressed downward by a helical spring L^2 in the 15 tubular holder and a screw L^3 at the upper end of said holder serves as an abutment and tensioning means for the spring. On the top of the offset portion H^5 of the plunger shank is secured a serrated member or file M against which the material L' is pressed. The member M is held in position by a member M' which is of inverted U shape to embrace the shank portion H^5 and has ears M^2 for clinching beneath said shank. Upwardly extending ears M^3 engage the opposite 20 ends of the member M to hold it in position and a down-struck portion M^4 engaging a notch in the shank portion H^5 holds this member from longitudinal displacement. Thus when the trigger is 25 drawn rearward the member M will move with it, and when the sear is released from the hook H^6 and the plunger snaps forward, the quick movement of the roughened or file face of the member M over the member L' will cause the sparking or 30 flash.

To give the appearance of a repeating fire arm the gun barrel is provided with radiating fins, assumed to be for the purpose of radiating the heat of the barrel. Some of these fins N are at 40 the rear end of the barrel, being formed by disks apertured to fit around a sleeve N' and having turned laterally extending flanges surrounding the aperture forming spacers between the disks. The parts are secured together by soldering and 45 the sleeve N' is slipped on to the barrel and wedged at the rear end thereof. There is also a flaring enlargement O at the forward or muzzle end of the barrel which is provided with surrounding disk fins O' similar to the fins N . The member O is sleeved over the forward end of the barrel and is secured thereto. This member in 50 addition to its supposed function of a heat dissipating means, performs the actual function of a megaphone for projecting forward the sound of 55 the report.

With the construction as described, it will be understood that when in use each time the trigger is pulled rearward it will compress the spring K and then release the plunger shank from the sear so that said spring will force the plunger forward in the air cylinder, compressing the air 60 therein. At the completion of the forward movement the extension H^4 of the plunger shank will unseat the disk F , causing a loud report. At the same time that the plunger and its shank are traveling forward, the member M being drawn over the sparking material L' will cause a rapid 65 succession of sparks, the light from which is observed through the translucent window covering D . To avoid any danger of sparks passing 70 through the crevice between the complementary sections of the flame, the flange G^6 has the downturned portion G^7 at its forward end which forms a shield.

What I claim as my invention is:

1. In a gun, an outer casing formed of complementary stampings including a barrel, a frame and handle of the gun, and an operating unit secured between said stampings comprising a plate having a U-shaped forward portion forming a guide and an inverted U-shaped portion at the rear also forming a guide offset from the aforesaid guide, a plunger, a plunger shank having a portion for traveling in the U-shaped guide and an offset rear portion for traveling in the inverted U-guide, a trigger pivotally attached to said plate below said offset portion of the shank, an inclined link pivotally attached at its lower end to said trigger and having at its rear portion a shoulder for engaging a downturned hook on the plunger shank, a helical spring surrounding said plunger shank, the latter being provided with an abutment for the rear end of said spring and an oblique flange on said plate in the path of the rear end of said link when moved rearward by the pulling of the trigger, being adapted to disengage the shoulder from the hook on the shank to permit the forward movement of the plunger under actuation of said helical spring. 10

2. In a gun, an outer casing formed of complementary stampings including a barrel, a frame and handle of the gun, and an operating unit secured between said stampings comprising a plate having a U-shaped forward portion forming a 15 guide and an inverted U-shaped portion at the rear also forming a guide offset from the aforesaid guide, a plunger, a plunger shank having a portion for traveling in the U-shaped guide and an offset rear portion for traveling in the inverted 20 U-guide, a trigger pivotally attached to said plate below said offset portion of the shank, an inclined link pivotally attached at its lower end to said trigger and having at its rear portion a shoulder for engaging a downturned hook on the plunger 25 shank, a helical spring surrounding said plunger shank, the latter being provided with an abutment for the rear end of said spring and an oblique flange on said plate in the path of the rear end of said link when moved rearward by 30 the pulling of the trigger, being adapted to disengage the shoulder from the hook on the shank to permit the forward movement of the plunger under actuation of said helical spring. 35

3. In a toy gun, a casing having integral barrel, frame and handle portions formed by complementary stampings, the frame portion having an upward extension provided with a window opening therein, a translucent closure for said 40 opening, a pop mechanism within said frame including an air compression plunger and rearwardly extending shank therefor, and sparking means including a member mounted on said shank and a cooperating member mounted on 45 said frame opposite said window whereby the movement of said shank to produce the pop will simultaneously display light through the translucent cover of said window. 50

4. In a toy gun, the combination with a casing 55 including integral barrel, frame and handle portions, said casing being formed of complementary stampings and provided with a window opening in the upper portion of the frame, a translucent cover for said window opening, pop 60

mechanism within said frame including an air compression plunger and a shank therefor having an upwardly offset rearwardly extending portion, a trigger pivoted within said frame below the offset portion of said shank, means actuated by said trigger for retracting said shank and then releasing the same, a spring for moving said plunger forward when released and sparking mechanism including a serrated member mounted on the offset portion of said shank to be movable therewith, a holder for sparking material mounted in said frame above said member on the shank and opposite said window opening, sparking material in said holder, means for resiliently pressing said material downward against said serrated member, a spring for moving said plunger in a forward direction and trigger actuated mechanism for retracting said plunger shank and then releasing the same to be moved forward by said spring whereby the release of said shank by said trigger mechanism will simultaneously move said plunger forward and display light through said window.

5. In a toy gun, a casing comprising integral barrel, frame and handle portions, said casing being formed by complementary stampings meeting in a central plane, a pop mechanism within said casing comprising a plate having a portion

located within said frame and a portion extending into said barrel and forming a plunger shank guide, a plunger in said barrel, a plunger shank engaging said guide, said shank having an upwardly offset portion within the frame terminating in a downturned hook, a guide on said plate for said offset portion of the plunger shank, a trigger pivotally mounted on said plate below said offset portion of the shank, a link pivotally connected to said trigger and extending upward and rearward therefrom, being provided with a shoulder for engaging said downturned hook constituting a sear, said link having a downwardly curved end portion, a guide on said plate in the path of said downwardly curved end portion adapted to disengage said sear from said hook after the rearward movement of said shank under actuation of said trigger and link, a serrated member mounted on the off-set portion of said shank, a holder for sparking material mounted in a flange on said plate above said offset portion of the plunger, means for resiliently pressing the sparking material downward in said holder against said serrated member and a translucent member covering an opening in said frame opposite said holder.
